UNITED STATES PATENT OFFICE

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed January 23, 1924. Serial No. 688,077.

My invention has relation to means for starting or cranking an engine such as an internal combustion engine, and more particularly to that part thereof known as the drive or transmission which transmits the power of a prime mover such as an electric motor to a part or member of the engine to be started, such as the flywheel thereof. The object of my invention is to provide a simple and efficient drive or transmission which is capable of a manual operation for engagement with the engine member. My drive contains novel features of construction resulting in novel operations and results, which will be apparent from the description hereinafter given.

In the drawings, Fig. 1 is a sectional elevation of an engine starter system including my new drive or transmission, the part being here illustrated in normal disengaged position; Fig. 2 a sectional elevation of the drive, illustrating the position of the parts under pinion abutting condition, with the driving member or pinion about to enter the flywheel; Fig. 3 a sectional elevation of the drive, illustrating the position of the parts during the cranking operation; Fig. 4 a sectional elevation of the drive proper; Figs. 5 and 6 sections on the corresponding section lines of Fig. 4; Fig. 7 a detail view partly in longitudinal section of the screw shaft; Fig. 8 a view of one end of the pinion; Fig. 9 a section on the line 9—9 of Fig. 8; Fig. 10 a view of one end of the nut; Fig. 11 an elevation of the nut with a portion thereof broken away; Fig. 12 an elevation of the drum 14 alone; Fig. 13 an elevation of a substitute or long shifting sleeve; Fig. 14 a detail of the locking ring alone; Fig. 15 an end elevation of the nut, drum and ring; and Fig. 16 an elevation of the nut and drum with the shell and ring in section.

For the purpose of a clear and definite disclosure of my invention, I have shown the same embodied in a certain specific structure, but it will be understood that such invention may be embodied in structures of somewhat different formation and arrangement without departing from the spirit and scope of my invention. It will also be understood that while I have shown my invention as applied to the so-called outboard type of drive, the

same may be applied to the inboard type of drive. Further, it will be understood that while I have shown my invention embodied in that type of drive known as the direct drive, in which the drive is directly connected with the extended armature shaft of an electric motor, my invention is also applicable to the indirect drive in which the drive or transmission is connected with a countershaft driven by the armature shaft.

Referring to the particular embodiment of my invention as illustrated in the drawings, the prime mover is an electric motor 1 provided with an extended armature shaft 2 and having a suitable switch and electrical connections which are of the usual kind and therefore need not be illustrated.

The drive or transmission is formed as an assembly which is readily applicable to and detachable from the extended armature shaft 2. This drive assembly comprises, in the present instance, a shaft which is in the form of a sleeve 3 (shown separately in Fig. 7) and which is mounted upon the armature shaft for rotary movement therewith and longitudinal movement thereof through a suitable medium as for instance the series of splines 4 on the armature shaft with their intervening grooves and the series of corresponding splines 5 and their intervening grooves in the bore of the sleeve 3. To one end of the sleeve 3 is secured, as by threading thereon, a stop nut 6 and at the other end, and also preferably by threading thereon a shifter sleeve 7. The sleeve 3 has a smooth surface portion 8 on which slides the driving member which is here in the form of a pinion 9 and it is also provided towards one end with coarse or steep pitch screw threads 10 by which the actuating or control member 11 is operatively connected with the screw shaft by being threaded thereto for longitudinal movement thereof and rotary movement therewith.

The control member 11, hereinafter called a nut, is operatively connected with the pinion by means of a friction clutch whereby the torque of the starting motor is transmitted from the screw shaft and the nut to the pinion and thence to the flywheel of the engine when the pinion is in cranking position.

tion. The clutch mechanism herein shown comprises two sets of clutch plates 12 and 13, the members of which alternate and which are connected respectively to the pinion 9 and a driving drum 14. The plates 13 interlock with the tongues 15 of the pinion and their intervening slots and the plates 12 interlock with the tongues 16 of the drum 14 and their intervening slots as illustrated in Figs. 4, 5, 10 6 and 9. A washer 17 is interposed between the innermost plate 12 and the bottom or vertical portion of the drum 14. In order to hold the friction plates in assembled position with respect to the pinion, a locking wire 18 is positioned in a circumferential groove 19 in the tongues 15, Figs. 4 and 9.

The drum 14 is secured to the nut 11 in a suitable manner as by means of the tongues 20 on the nut interfitting with corresponding 20 tongues 21 in the central bore of the drum, with the projecting lip 20^a riveted over into the recess 14^a. However, as is obvious, the nut 11 and drum 14 may be made in one piece, if desired.

25 The friction clutch assembly is held together in a suitable manner as by means of the shell 22 having an outer radial flange fitting over the outermost friction plate and an inner flange within which is introduced 30 a locking wire or ring 23 bearing against the drum 14. By preference a yielding pressure is exerted upon the nut 11 as by means of the coiled spring 24 interposed between its outer flange 25 and the shifter sleeve 7.

35 The drive assembly is adapted to be shifted manually or pedally and I will hereinafter refer to such action as a manual operation, using that term broadly to cover both operations. Any suitable manual shifting means 40 which is also capable of operating the usual motor switch may be employed and in the present instance, I have shown a portion of such a means such as a lever 26 pivoted at 27 on the bracket 28 which is secured to the 45 motor frame and which also provides the bearing for the outer end of the armature shaft 2. The lower end of this lever 26 is made in the form of a yoke 29 terminating in rollers 30 which are positioned between 50 the flanges 31 of shifting sleeve and are thereby operatively connected therewith.

Describing the cycle of operation of my drive or transmission and beginning with the parts in their normal disengaged position 55 shown in Fig. 1, the operator manually actuates the lever 26 whereupon the entire drive assembly is slid longitudinally along the armature shaft 2 by reason of the splined connection. In the event of perfect register 60 between the pinion teeth and the teeth of the flywheel, the pinion will go into full mesh as illustrated in Fig. 3, at or about which time the starting motor is operated by the closing of the switch connection either as a separate 65 manual operation or as incidentally to the

operation of the lever 26, whereupon the pinion will be rotated to crank the engine through its flywheel. In this cranking operation, the torque will be transmitted through the screw shaft nut 11, drum 14, washer 17, and friction plates 12, 13 to the pinion 9. When the pinion is in cranking position and the starting motor is operated, the nut 11 has a screw jack action upon the friction plates by reason of the screw threads 10. In this operation, the spring 24 serves to initiate the above described screw action, inasmuch as it maintains frictional contact between the clutch plates, which frictional contact is thereafter automatically increased by the pressure due to the longitudinal component of the torque resistance transmitted through the screw threads, in accordance with the resistance of the flywheel so that a torque will be transmitted by the clutch sufficient to break loose the flywheel from stationary position and to rotate it.

When the engine starts on its own power and the flywheel rotates the pinion which now becomes the driven member, the screw jack action will be relieved and likewise the frictional resistance between the clutch plates due to such action will be relieved, with the result that the pinion will be driven freely. When the operator relieves the pressure upon the lever 26 and the shifting means, the drive assembly will be restored to normal position, (in suitable manner, as by a spring 32) the pinion being thereupon disengaged from the flywheel.

In the event of abutting of the pinion teeth and the flywheel teeth, the shifter sleeve 7 and consequently the screw shaft will continue their longitudinal movement to the left, and, owing to the provision of the steep pitch of screw thread, the pinion, whose longitudinal movement has been arrested, will be rotated slightly and sufficiently to result in register between the teeth of the pinion and flywheel. The position of the parts at this particular stage is illustrated in Fig. 2. The pinion will thereupon move longitudinally with the screw shaft and go into full mesh with the flywheel.

While the shifting sleeve 7 may obviously be made integral with the screw shaft, I prefer to make it as a separate piece attachable thereto, in order that the drive assembly may be made standard for all installations which can be taken care of by making the sleeve portion of this shifter 7 of the desired length and diameter to accommodate the relative position of the shifting yoke 29 or the like. A sleeve 33 elongated for such purpose is shown in Fig. 13.

I prefer to make the locking ring as in Figs. 14 and 15, wherein it is shown as having an offset end or tail piece which presses against the outer face of the drum as illustrated in Fig. 16. This construction provides an ef-

- mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates, one set being interlocked with the driving member, and the control member having a drum extension with which the other set of plates is interlocked. 5
11. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates, one set being interlocked with the driving member, and the control member having a drum extension with which the other set of plates is interlocked, a shell fitting over the drum extension and having flanges at opposite ends, one flange holding the clutch plates in position, and a locking ring located between the other flange and the corner of the drum extension to hold the shell in place, said ring being a split ring with one end offset to bear against such drum extension. 15
12. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates, one set being interlocked with the driving member, and the control member having a drum extension with which the other set of plates is interlocked, said extension encompassing said friction clutch. 20
13. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates, one set being interlocked with the driving member, and the control member having a drum extension with which the other set of plates is interlocked, and a shell fitting over the drum extension and having a flange to hold the clutch plates in position. 25
14. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates, one set being interlocked with the driving member, and the control member having a drum extension with which the other set of plates is interlocked, a shell fitting over the drum extension and having flanges at opposite ends, one flange holding the clutch plates in position, and a locking ring located between the other flange and the corner of the drum extension to hold the shell in place. 30
15. An engine starter drive including a rotatable shaft, a sleeve mounted thereon for longitudinal movement thereof and rotary movement therewith, a stop on the sleeve, a pinion loosely mounted on the sleeve and positioned against the stop, a control member mounted on the sleeve for longitudinal movement thereof and rotary movement therewith, and a friction clutch interposed between the pinion and control member and mounted thereon, and manually operated means for shifting the sleeve longitudinally of the shaft. 35
16. An engine starter drive including a rotatable shaft, a sleeve mounted thereon for longitudinal movement thereof and rotary movement therewith, a stop on the sleeve, a pinion loosely mounted on the sleeve and positioned against the stop, a control member mounted on the sleeve for longitudinal movement thereof and rotary movement therewith, and a friction clutch composed of plates in two sets, one set being interlocked with the pinion and the other set with the control member, and manually operated means for shifting the sleeve longitudinally of the shaft. 40
17. An engine starter drive including a rotatable shaft mounted for longitudinal and rotary movements, a pinion loosely mounted on and normally positioned at one end of the shaft and having longitudinally extending tongues and grooves at one end, a nut threaded on the shaft for longitudinal movement thereof and rotary movement therewith, and a friction clutch composed of plates in two sets, one set being connected with the nut and the other set having a bore with corresponding tongues and grooves interlocking with the first mentioned tongues and grooves in combination with manually operated means for moving such shaft longitudinally. 45
18. An engine starter drive including a rotatable shaft mounted for longitudinal and rotary movements, a pinion loosely mounted on and normally positioned at one end of the shaft and having longitudinally extending tongues and grooves at one end, a nut threaded on the shaft for longitudinal movement thereof and rotary movement therewith, and a friction clutch composed of plates in two sets, one set being connected with the nut and the other set having a bore with corresponding tongues and grooves interlocking with the first mentioned tongues and grooves in combination with manually operated means for moving such shaft longitudinally. 50

ficient locking device which also holds the parts together to prevent rattle and which permits of easy assembly and disassembly.

I claim:

5. 1. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, yielding means constantly urging the control member towards the driving member, and a friction clutch interposed between the control member and the driving member.
10. 2. An engine starter drive including a rotatable shaft mounted for longitudinal and rotary movements, a driving member loosely mounted on the shaft and adapted to engage a member of the engine to be started, a control member threaded upon the shaft for longitudinal movement thereof and rotary movement therewith, yielding means constantly urging the control member towards the driving member, and a friction clutch interposed between the control member and the driving member.
15. 3. An engine starter drive including a rotatable shaft mounted for longitudinal and rotary movements, a driving member loosely mounted on the shaft and adapted to engage a member of the engine to be started, a control member threaded upon the shaft for longitudinal movement thereof and rotary movement therewith, a spring constantly urging the control member towards the driving member, and a friction clutch interposed between the control member and the driving member.
20. 4. An engine starter drive including a rotatable shaft mounted for longitudinal and rotary movements, a driving member loosely mounted on the shaft and adapted to engage a member of the engine to be started, a control member threaded upon the shaft for longitudinal movement thereof and rotary movement therewith, a spring constantly urging the control member towards the driving member, and a friction clutch interposed between the control member and the driving member.
25. 5. An engine starter drive including a rotatable shaft mounted for longitudinal and rotary movements and having a fixed abutment, a driving member loosely mounted on the shaft and adapted to engage a member of the engine to be started, a control member threaded upon the shaft for longitudinal movement thereof and rotary movement therewith, a compression spring interposed between the control member and the fixed

abutment on the shaft, and a friction clutch positioned between the control member and the driving member.

6. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch between the control member and the driving member, the control member cooperating with the clutch to build up a frictional resistance sufficient to transmit driving torque to the driving member when such shaft is the driving element and to release the clutch when the engine is started and the driving member becomes the driver.

7. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, yielding means urging the control member towards the driving member, and a frictional clutch between the control member and the driving member, the control member cooperating with the clutch to build up a frictional resistance sufficient to transmit driving torque to the driving member when such shaft is the driving element and to release the clutch when the engine is started and the driving member becomes the driver.

8. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch having members cooperating with the driving member and control member respectively.

9. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and a friction clutch interposed between the control member and the driving member, said clutch comprising two sets of plates one set having tongue and groove connection with the driving member and the other set having tongue and groove connection with the control member.

10. An engine starter drive including a rotatable shaft, mounted for longitudinal and rotary movements, a driving member loosely

- shaft and having longitudinally extending tongues and grooves at one end, a nut threaded on the shaft for longitudinal movement thereof and rotary movement therewith, and a friction clutch composed of plates in two sets, one set being connected with the nut and the other set having a bore with corresponding tongues and grooves interlocking with the first mentioned tongues and grooves, and means for detachably holding said other set of plates upon the pinion in combination with manually operated means for moving such shaft longitudinally. 10
19. An engine starter drive including a rotatable shaft mounted for longitudinal and rotary movements, a pinion loosely mounted on and normally positioned at one end of the shaft and having longitudinally extending tongues and grooves at one end, a nut threaded on the shaft for longitudinal movement thereof and rotary movement therewith and having an extension provided with tongues and grooves, and a friction clutch composed of plates in two sets, one set being interlocked 20 with the tongues and grooves of the pinion and the other set being interlocked with the tongues and grooves of said extension in combination with manually operated means for moving such shaft longitudinally. 25
20. An engine starter drive including a rotatable shaft mounted for longitudinal and rotary movements, a pinion loosely mounted on and normally positioned at one end of the shaft and having longitudinally extending 30 tongues and grooves at one end, a nut threaded on the shaft for longitudinal movement thereof and rotary movement therewith, said nut having a drum portion, and a friction clutch composed of plates in two sets, one set 35 being interlocked with the tongues and grooves of the pinion and the other set being interlocked with the drum in combination with manually operated means for moving such shaft longitudinally. 40
21. An engine starter drive including a rotatable shaft, a sleeve mounted thereon for longitudinal movement thereof and rotary movement therewith, a stop on the sleeve, a pinion loosely mounted on the sleeve and positioned against the stop, a control member 45 mounted on the sleeve for longitudinal movement thereof and rotary movement therewith, a friction clutch interposed between the pinion and control member and mounted thereon, and manually operated means for shifting the sleeve longitudinally of the shaft, including a shipper sleeve slideable on the shaft and made separate from, but attachable to the drive sleeve. 50
22. An engine starter drive including a rotatable shaft mounted for longitudinal and rotary movements, a driving member loosely mounted on the shaft and adapted to engage a member of the engine to be started, a control member mounted on the shaft for longi- 55
- tudinal movement thereof and rotary movement therewith, and operatively connected with the driving member, and means associated with the control member for the conversion of the longitudinal movement of the shaft into rotary movement of the control member and the driving member in event of abutting of the driving member and engine member. 60
23. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and operatively connected with the driving member, and means associated with the control member for the conversion of the longitudinal movement of the shaft into rotary movement of the control member and the driving member in event of abutting of the driving member and engine member. 65
24. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and operatively connected with the driving member, and means associated with the control member for the conversion of the longitudinal movement of the shaft into rotary movement of the control member and the driving member in event of abutting of the driving member and engine member, said means including a screw thread connection between the control member and the shaft. 70
25. An engine starter drive including a rotatable shaft mounted for longitudinal and rotary movements, a driving member loosely mounted on the shaft and adapted to engage a member of the engine to be started, a control member mounted on the shaft for longitudinal movement thereof and rotary movement therewith, and operatively connected with the driving member, and means associated with the control member for the conversion of the longitudinal movement of the shaft into rotary movement of the control member and the driving member in event of abutting of the driving member and engine member, said means including a screw thread connection between the control member and the shaft and a spring urging the control member towards the driving member. 75
26. An engine starter drive formed as a unitary assembly adapted to be slipped upon a driving shaft and comprising a hollow rotatable shaft adapted to be driven by such 80

- driving shaft, a driving member loosely mounted upon the hollow shaft, a control member mounted upon such hollow shaft for longitudinal movement thereof and rotary movement therewith, operating connection between the driving member and the control member, and a shipper means at one end of the hollow shaft whereby such assembly may be shifted longitudinally.
27. An engine starter drive formed as a unitary assembly adapted to be slipped upon a driving shaft and comprising a hollow rotatable shaft adapted to be driven by such driving shaft, a driving member loosely mounted upon the hollow shaft, a control member mounted upon such hollow shaft for longitudinal movement thereof and rotary movement therewith, a friction clutch forming the operating connection between the driving member and the control member, a stop nut at one end of the hollow shaft adjacent the driving member, and a shipper device at the other end thereof adjacent the control member whereby such assembly may be shifted longitudinally.
28. An engine starter drive including a driving member, a control member, a friction clutch interposed between and directly cooperating with the driving member and the control member and controlled by the latter, said members and clutch being formed as a unit assembly, and a rotatable and longitudinally movable member on which said assembly is mounted to move therewith as a unit.
29. An engine starter drive including a driving member, a control member, a friction clutch interposed between and directly cooperating with the driving member and the control member and controlled by the latter, said members and clutch being formed as a unit assembly, a rotatable and longitudinally shiftable member on which said assembly is mounted to move therewith as a unit, and a shaft member operatively connected with the last said member to rotate it and permit its longitudinal shifting movement.
30. An engine starter drive including a driving shaft, a driving member mounted for rotary movement and for longitudinal movement, a control member adapted to cooperate with the driving member and threaded on said shaft for rotary movement and for longitudinal movement, yielding means for urging the control member towards the driving member, and a torque transmitting device interposed between the control member and the driving member and controlled by said control member for one-way torque transmission.
31. An engine starter drive including a rotatable shaft mounted for longitudinal and rotary movements, a driving member loosely mounted on the shaft and adapted to engage a member of the engine to be started, a control member threaded on the shaft for longitudinal movement thereof and rotary movement therewith, yielding means constantly urging the control member towards the driving member, and a torque transmitting device interposed between the control member and the driving member and controlled by said control member for one-way torque transmission.
32. An engine starter drive including a driving member, a control member, a friction clutch interposed between and directly cooperating with the driving member and the control member and controlled by the latter, said members and clutch being formed as a unit assembly, a rotatable and longitudinally movable member on which said assembly is mounted to move therewith as a unit, and means for actuating said control member to vary the torque-carrying capacity of said clutch.
33. An engine starter drive including a driving member, a control member, a friction clutch interposed between and directly cooperating with the driving member and the control member and controlled by the latter, said members and clutch being formed as a unit assembly, a rotatable and longitudinally movable member on which said assembly is mounted to move therewith as a unit, and means interposed between the last said member and said control member for actuating said control member to vary the torque-carrying capacity of said clutch.
